UNITED STATES PATENT OFFICE

JAIRUS S. RICHARDSON, OF SHEBOYGAN FALLS, WISCONSIN, ASSIGNOR TO RICHARDSON BROTHERS COMPANY, OF SHEBOYGAN FALLS, WISCONSIN, A CORPORATION OF WISCONSIN

EXTENSION TABLE

Application filed February 14, 1927. Serial No. 163,036.

The invention relates to tables and more particularly to extension dining tables. It is customary in the manufacture of extension tables to employ slides which are usually supplied as self-contained slide assemblies adapted to be suitably secured to the table top. Such slide assemblies consist of several slide members grouped together and are somewhat expensive in addition to being 10 of more or less complicated and cumbersome construction, permitting neither compact shipment in knock-down condition nor facility in the assembly or taking down of the table.

15 It is an object of the present invention to provide an extension table of simple, rigid, light-weight and inexpensive construction in which the rails of the table frame also form slide members to obviate the disadvantages of 20 separate slide assemblies.

Another object is to provide a knock-down extension table which can be conveniently and quickly assembled and taken down and which can be packed for shipment in a 25 comparatively small and compact container.

The invention further consists in the several features hereinafter set forth and more particularly defined by the annexed claims.

In the accompanying drawings, Fig. 1 is 30 a longitudinal sectional elevation of an extension table embodying the invention;

Fig. 2 is a bottom plan view of the table in extended position;

Fig. 3 is a transverse sectional view taken 35 along the joint in the top, parts being broken away and parts being shown in section; and

Fig. 4 is a sectional disassembled view of the table parts as they appear in packed relation ready for shipment.

40 In these drawings, the numeral 10 designates a set of table legs which have their upper end portions secured as usual in lateral abutment with the ends of side and end rails 11 and 12, respectively. The side and end rails are 45 secured together at their adjacent ends in a well known manner by corner brackets 13 which receive the customary leg-attaching screws or studs 14 by means of which the legs may be conveniently dismounted when the 50 table is to be taken down. There are two sep-

arable aligned side rails 11 at each side of the table, and each end rail 12 with its two attached side rails forms a separable frame section complementary to the frame section formed by the other end rail and its two attached side rails. A table top section 15 forming a part of each frame section is secured to the upper edges of the rails in each frame section, preferably by means of screws 16, as seen in Fig. 3, projecting from the rails 55 upwardly into the table top.

Each side rail 11 has a longitudinal groove 17 formed in its inner face, and the aligned grooves 17 in each pair of aligned side rails receive a longitudinal rib 18 projecting from 60 one face of a slide member 19, the other face of the slide member being provided with a similar longitudinal rib 20. In order to retain the slide members 19 relatively slidable in engagement with the grooved side rails, 65

guide blocks 21 are secured to the under face of the table top sections near the meeting edges thereof and in spaced parallel relation to the adjacent side rails, and each guide block is provided with a longitudinal groove 22 receiving the rib 20 of the adjacent slide member 19. The guide blocks 21 are secured to 70 the table top by means of screws 23 projecting upwardly into the table top as seen in Fig. 3. Each slide member 19 is preferably of elongated cruciform cross section as seen in Fig. 75

3, although it may be of inverted T-shaped cross-section, and has its upper edge on the same level as the under face of the table top sections in order to support filler leaves 24 when the table frames are drawn apart. In 80 order to limit the separating movement of the table frames, a removable threaded pin or dowel 25 is screwed into the end portion of each slide member 19 to project laterally therefrom in position to engage the end of the adjacent guide block 21, which may be provided with a notch 26 at its end to receive the pin and thereby extend the range of movement of the table sections without need for shortening the block. If an additional center 85

leg 10' is found desirable in some cases, this may be conveniently attached to a cross member 27 which is secured at its ends to the bot- 90

tom edges of the slide members 19, as seen in Fig. 3.

In extending the table from the contracted position of Fig. 1, the table sections are urged apart to the position of Fig. 2 during which movement the slide members have a relative sliding movement in the grooves 17 formed in the side rails 11 and in the grooves 22 of the guide blocks 21. The filler leaves 24 are then interposed between the table top sections 15 and are supported in position on the upper edges of the slide members 19.

When taking down the table for shipment, the legs 10 are removed in the usual manner and the threaded pins or dowels 25 are then detached from the end portions of the slide members 19, which thereupon permits the slide members to be withdrawn and the table sections to be entirely separated. The two table sections are then placed one next to the other with the bottom edges of the front and side rails 11 and 12 facing each other, the dismounted legs and slide members being placed along the outer sides of the end rails and the filler leaves resting on one of the table top sections. Suitable packing material may be interposed between the various parts to prevent marring of finished surfaces. The entire group of table parts in the above-noted relation can be placed in an exceptionally compact shipping container 28, as seen in Fig. 4, which greatly facilitates shipment and storage.

The invention provides an extension table which combines simple and inexpensive construction with rigidity and light-weight, and affords convenient assembly and taking down in addition to facility in shipment and storage.

What I claim as new and desire to secure by Letters Patent is:

1. In an extension table, the combination of a pair of complementary table frames including at each side a pair of aligned side rails each having a longitudinal groove on its inner face, guide blocks secured to said frames behind and in parallel relation to the adjacent end portions of said aligned side rails and each having a longitudinal groove facing the adjacent side rail, and a leaf-supporting slide member retained by said guide blocks along the inner face of each pair of aligned side rails and each slide member including longitudinally-extending ribs slidably fitting in the grooves of said side rails and guide blocks to permit the relative retraction of said frames.

2. In an extension table, the combination of a pair of complementary table frames including at each side a pair of aligned side rails each having a longitudinal groove on its inner face, a slide member extending and retained along the inner face of said aligned side rails and having longitudinally extending ribs on opposite sides, one of which slid-

ably fits in said longitudinal grooves of the side rails, guide blocks secured to said frame behind and in parallel relation to the end portions of said aligned side rails and each having a longitudinal groove facing the adjacent side rail and receiving slidably therein the adjacent rib of said guide member, and stop pins each secured adjacent an end of said slide member and projecting therefrom to be engageable with the outer ends of said guide blocks for limiting the withdrawal of said frames, each guide block having adjacent its stop-abutting end a notch receiving said stop pin therein to extend the range of retraction of said table frames without reducing the bearing engagement of said guide members with said slide member.

3. In an extension table, the combination of a pair of complementary table frames including at each side a pair of aligned side rails each having a longitudinal groove on its inner face, a slide member slidably retained along the inner face of each pair of aligned side rails and slidably fitting in said grooves to permit the relative retraction of said table frames, guide blocks fixedly secured to each frame behind and in parallel relation to the adjacent end portions of said aligned side rails for lateral slidable engagement with and retention of said slide members in the grooves of said side rails, and removable stops carried at the end portions of said slide members and engageable with said guide blocks to limit the retraction of said frames.

4. In an extension table, the combination of a pair of complementary table frames including at each side a pair of aligned side rails each having a longitudinal groove on its inner face, a pair of parallel slide members bridging said table frames and respectively retained in slidable relation along the inner face of each pair of said aligned side rails and each slide member having a rib portion slidably fitting in said grooves to permit the relative retraction of said table frames, and a pair of guide blocks fixedly secured to each frame behind and in parallel relation to the adjacent end portions of said aligned side rails for lateral slidable engagement with and retention of said slide members in the grooves of said side rails.

In testimony whereof, I affix my signature.

JAIRUS S. RICHARDSON.
